UNITED STATES PATENT OFFICE.

JOSEPH GOODMAN, OF WHITNEYVILLE, CONNECTICUT, ASSIGNOR TO THE MT. CARMEL MFG. CO., OF MOUNT CARMEL, CONNECTICUT, A CORPORATION OF CONNECTICUT.

DOOR HANDLE.

Application filed December 31, 1924. Serial No. 759,034.

This invention relates to handles, and particularly handles of the type used on automobile doors, and has for an object to provide a handle which will be simple in construction and may be manufactured at low cost, which may be constructed to a large extent of sheet metal, and which will be neat and attractive in appearance.

With the foregoing and other objects in view, I have devised the construction illustrated in the accompanying drawing forming a part of this specification, similar reference characters being employed throughout the various figures to indicate corresponding elements. In this drawing,

Fig. 1 is a partial side elevation and a partial section of the handle complete shown mounted on a door.

Fig. 2 is a front elevation thereof.

Fig. 3 is a transverse section through the handle substantially on line 3—3 of Fig. 2.

Fig. 4 is a longitudinal section through the handle with the finishing block separated therefrom and indicating the method of assembling.

Fig. 5 is a similar view with the finishing block placed in position, and

Fig. 6 is a transverse section substantially on line 6—6 of Fig. 5, and showing how the finishing block is clamped in position.

A section of a door, such as an automobile door, is shown at 10 to which the escutcheon 11 is secured by any suitable means, such as screws 12, this escutcheon being preferably stamped and formed from a piece of sheet metal. It is provided with an outwardly extending concavo-convex flange 13 having an opening 14 therethrough for passage of the latch operating spindle 15 to any suitable type of lock, not shown, this spindle in the usual construction being substantially square in cross section.

Secured to the outer end of this spindle for operating the same is a cross bar of improved construction. This cross bar comprises a channel member 16, preferably formed from a strip of sheet metal, and provided with inwardly directed overhanging flanges 17 along the side edges. The central wall of the channel member is provided with an opening 18 for passage of the spindle 15, and the end of this spindle is rigidly secured to a bar 19, preferably a strip of metal, which extends longitudinally in the channel. It is preferred to secure this bar

to the spindle by reducing the end of the spindle, as shown at 20, to provide a shoulder 21 and passing this reduced end through an opening in the bar 19 where it is riveted or headed over as shown to secure the bar against the shoulder to form a rigid connection.

In assembling, means must be provided for securely fastening the channel member to the bar and spindle, and also to fill up the channel to give a neat and attractive appearance, which filling means also strengthens the cross bar of the handle. It will be noted from Fig. 6 that the side walls 22 of the cross bar are spread somewhat to allow for the insertion in the channel of a strip or block 23 of a material which is hard at ordinary temperatures but is softened or made more or less plastic by heating, such for instance, as hard rubber. This block or slab is formed substantially the shape shown in Figs. 4, 5 and 6 with a recess 24 in the back wall thereof for the bar 19. This block or strip of the hard rubber or other material which is hard at ordinary temperatures but

may be made more or less plastic by heating, is inserted in the channel member when heated and thus plastic as shown in Figs. 5 and 6. The side walls 22 and flanges 17 are then pressed inwardly toward each other to securely clamp this plastic block within the channel, which completely fills the channel and encloses the bar 19. As the block or strip 23 is plastic the flanges 17 will be forced into the opposite sides of this strip and the space between them will be filled with this material as shown in Fig. 3. The side walls and flanges may be pressed to this position between dies 25 of a suitable power press, as shown in Fig. 6. The plastic block or slab 23 is then allowed to cool so that it becomes hard and rigid, and the exposed surface 26 thereof together with the surfaces of the metal channel member may be finished by grinding and polishing.

It will be noted that as the strip or slab 23 is plastic when the sides of the channel member are pressed inwardly to grip the slab, that all of the space within the channel is completely filled with this plastic material, so that the exposed surface 26 after finishing is flush with the outer surface of the flanges 17 of the channel member. Thus there may be formed a smooth continuous surface and as the metal may be given any

finish desired, such as a nickel plated and polished surface, a neat and attractive appearance is secured. With a black rubber strip extending down through the center of the cross bar the contrasting colors are very attractive. As the slab 23 is clamped between the sides of the channel member it is forced tightly about the bar 19 secured to the shank 15, and as the plastic slab hardens it gives the effect of a solid cross bar, and also the bar 19 is very rigidly and tightly secured in the channel member giving a very strong and reliable connection between the cross bar and the latch operating spindle. Referring to Fig. 1, the portion of the spindle 15 between the escutcheon and the cross bar is enclosed by a metal tube 27, preferably tapered as shown as it gives a better appearance, and the opposite ends of this tubular element rest against the walls of the channel member 16 and the convex outer surface of the flange 13 of the escutcheon. A second tubular member or collar 28 embraces the spindle on the other side of the escutcheon and is secured thereto by any suitable means such as pressing the walls thereof into notches 29 in the corners of the spindle, and the outer end of this collar engages the inner or concave wall of the flange 13. To give a better bearing surface this end is preferably flared somewhat as shown at 30. This construction is a very simple one and the bearing of the members 27 and 28 on opposite sides of the concavo-convex flange 13 will allow the handle or spindle to rock in all directions relative to the escutcheon and allow it to assume the proper position with respect to the lock regardless of any inclination to the surface of the door. The outer end of member 27 may be centered and retained in this position by means of a rib or head 31 formed in the channel member 16 and surrounding the end of the tubular member. It will be apparent from the foregoing description that the handle is of very simple construction and may be made to a large extent of sheet metal, but that when it is assembled it gives a very rigid and strong construction and one which with simple finishing operations may be made very neat and attractive in appearance.

Having thus set forth the nature of my invention, what I claim is:

1. A handle comprising a channel shaped cross bar provided with inturned flanges along the sides thereof and having an opening in the central wall, a spindle extending through said opening, a bar secured to the spindle and extending longitudinally in the channel, and a block of material hard at ordinary temperatures and plastic when heated filling said channel and clamped about said bar by said flanges while in the plastic condition. 65

2. A handle comprising a sheet metal channel shaped cross bar having inturned flanges along the sides thereof and an opening in its central wall, a spindle extending through said opening, a bar secured to the spindle and extending longitudinally in the channel, and a block of hardened plastic material clamped in the channel about said bar by said flanges. 70

3. A handle comprising a channel shaped cross bar provided with inturned flanges along the sides thereof and having an opening in the central wall, a spindle extending through said opening and having a reduced end forming a shoulder, a bar having an opening for said reduced end and riveted against said shoulder, said bar extending longitudinally in the channel, and a block of material hard at ordinary temperatures and plastic when heated filling said channel and clamped about said bar by said flanges while in the plastic condition. 75

4. A handle comprising a sheet metal channel shaped cross bar having inturned flanges along the sides thereof and an opening in its central wall, a spindle extending through said opening, a bar secured to the spindle and extending longitudinally in the channel, and an insert comprising a slab seated in the channel, and clamped therein against the bar by the side walls of the channel member to secure the spindle to the channel shaped cross bar. 80

5. A handle comprising a sheet metal channel shaped cross bar having inturned flanges along the sides thereof, a spindle, a bar secured to the spindle and extending longitudinally in the channel, and a block of hardened plastic material clamped in the channel about said bar by said flanges. 85 100 105

In testimony whereof I affix my signature.

JOSEPH GOODMAN.
